UNITED STATES PATENT OFFICE.

GEORGE O. SEWARD, OF NIAGARA FALLS, NEW YORK, ASSIGNOR TO AMERICAN MAGNESIUM CORPORATION, OF NIAGARA FALLS, NEW YORK, A CORPORATION OF NEW YORK.

ELECTROLYTIC APPARATUS.

1,408,142.

Specification of Letters Patent. Patented Feb. 28, 1922.

Application filed October 11, 1917, Serial No. 196,027. Renewed May 3, 1921. Serial No. 466,532.

To all whom it may concern:

Be it known that I, GEORGE O. SEWARD, a citizen of the United States of America, residing in Niagara Falls, in the county of 5 Niagara and State of New York, have invented certain new and useful Improvements in Electrolytic Apparatus, of which the following is a specification.

This invention provides an electrolytic 10 furnace adapted for electrolyzing a bath of molten salts or compounds, for example of haloid salts; and particularly salts of metals which are lighter than the molten bath, so that upon being electrodeposited or separated the metal rises through the bath and 15 floats upon the top of the electrolyte. The apparatus is designed especially for use in practicing a process for electrodepositing magnesium which is set forth in another 20 application for patent which I have prepared and which is intended to be filed concurrently, or substantially so, with the present application (filed November 19, 1917, Serial No. 202,821).

25 In a prior United States Patent No. 880,489, patented February 25, 1908, to Franz von Kugelgen and George O. Seward, there is described and claimed an electrolytic process of producing magnesium or 30 alloys thereof, according to which magnesium oxide is added to a molten bath containing magnesium fluorid and a fluorid of a metal or metals electropositive to magnesium. My present invention relates to apparatus adapted to perform operations of 35 the above general character.

Figure 1 of the accompanying drawing is a transverse section of the preferred construction of an electrolytic furnace according to the present invention;

Fig. 2 is a plan of the furnace.

In the drawings, 1 represents a metallic vessel or container for the bath, which is preferably an unlined vessel of wrought-iron having preferably a curved bottom and upright ends, and preferably supported upon blocks 2, 2 in such manner as to afford a free circulation of air beneath the vessel in order to avoid overheating. The bath solidifies to a greater or lesser extent upon the bottom, as indicated at 3, the central portion or pool 4 remaining fluid under the operating conditions. 5, 5 represent the cathodes, which may consist of iron or steel cast-

ings extending longitudinally of the vessel 55 and projecting through apertures 6 in its bottom. Preferably an intervening layer of insulating material, such as asbestos, 20, is interposed between each cathode casting 5, and the vessel 1. The mass of solidified salts 60 3 is effective to prevent any leakage of electrolyte around the cathodes. The upper edges of the cathodes may be beveled, as indicated, in order to facilitate the upward flow and detachment of the molten magnesium. 65

9, 9 represent the anodes, which may be of carbon or graphite, and which depend into the bath between the cathodes and out of vertical alignment therewith. The drawing shows two rows of the anodes 9, 9, which is 70 preferable. Any desired or suitable number of anodes may be provided. 10 indicates a layer of magnesium oxid or of magnesium carbonate floating upon the surface of the bath and serving not only to retain the heat, 75 but also as a primary source of raw material for the production of magnesium, the magnesium oxid either dissolving progressively in the bath and undergoing electrolysis therein, or uniting with fluorin liberated by 80 the current and hence restoring the magnesium fluorid content of the bath. In case magnesium carbonate is used it is eventually converted into magnesium oxid by calcination. Either magnesium oxid or magnesium 85 carbonate is effective to protect the anodes which are otherwise subject to strong attack at or near the surface of the bath.

Cooling pipes 11 are arranged in two vertical series in planes between those of the 90 anodes and those of the cathodes. The function of these is to chill and thereby to solidify a limited portion of the bath to form vertical partitions of insulating material.

The construction is such that above the 95 cathodes are formed hoods or collecting chambers 12 for receiving the molten magnesium which ascends from the cathodes. In the construction shown, these are formed of cast metal or sheet metal casings 13 located 100 near the surface of the bath and suitably cooled. They are shown as supported from the upper edges of the side walls of the vessel 1. The inner wall 14 of each hood is located sufficiently adjacent to the cooling 105 pipes 11 so that the mass of solidified salts extends to the wall 14, and seals the space between this wall and the pipes. The pipes

11 also extend preferably below the bottom of the hood so as to more effectually separate the space 12 for the magnesium from the anode chamber between the two series of 5 cooling pipes 11. The casings 13 are preferably filled or packed with insulating material (for example kieselguhr), in order to prevent loss of heat and undesirable cooling. The molten metal may be drawn off continuously, or intermittently, from tap holes 16 10 communicating with the space within the collecting hood 12.

As a convenient means for supporting the tank and making the current connection with 15 the cathodes, the invention provides a construction, shown in Fig. 1, wherein each cathode 5 is formed with shoulders or ledges 17 for receiving the weight of the vessel, and with a preferably flat bottom 18 which rests 20 on a copper bus-bar which is formed as a flat plate, which in turn rests upon the supporting block 2. As the plate 19 has a large area of contact with the bottom of the cathode, the current readily flows from one 25 to the other. As the whole weight of the vessel and its contents comes upon the contacting surfaces of 18 and 19, a good electrical contact is assured.

The process to be practiced with this construction of electrolytic cell or furnace is 30 fully set forth in my companion application above referred to. Suffice it here to say that for the production of magnesium, the bath or electrolyte should be composed of suitable 35 fluorids, such that the molten bath will have a sufficient specific gravity to cause the produced magnesium to rise constantly to the surface. This bath is maintained molten by a suitable current, a temperature of 900° 40 to 1000° C. being found suitable. At the same time a sufficient flow of water is maintained through the cooling pipes 11 to insure an incrustation of congealed salt being maintained around these pipes. As the source 45 of heat is between the electrodes, no difficulty is experienced in maintaining the layer 3 of incrusted salt as a lining for the tank itself. The layer 10 of magnesium oxid or carbonate is replenished from time to time. 50 The bath of molten magnesium accumulates within the chambers or hoods 12, tap holes 16 being provided which are opened up at intervals to tap off the molten metal. By thus enclosing the molten magnesium within 55 in the hoods 12 it is protected against any possibility of loss by burning.

The anodes are best arranged so that they may be individually fed downwardly into the electrolyte as they are oxidized and consumed. For this purpose they are carried by rods 170, suitably connected to them and suitably fastened to a bus-bar 180. The clamping and adjusting means are not shown, as such means are well known in the 60 art.

The use of separately adjustable anodes depending into the electrolyte and surrounded thereby is practically necessary, so that they can be fed down from time to time as required, without interfering with the continuous operation of the furnace. 70

It will be obvious that the proportions and arrangement may be considerably varied according to circumstances, and within the skill and judgment of those skilled in this 75 art, without departing from the invention.

It will be apparent from Fig. 1 that the electrolytic cell illustrated is in effect a double electrolytic furnace, having duplicate anode series and duplicate cathodes. The 80 cathode and the anodes on one side of the center could be omitted or disused without necessarily departing from the invention.

What I claim is:

1. An electrolytic apparatus for producing a metal lighter than the electrolyte, comprising a vessel for containing a molten fluorid bath, having an insulating layer of congealed salt on its bottom, a cathode projecting upwardly through such layer into the vessel, individually adjustable anodes depending into the vessel out of vertical alignment with the cathode, a collecting chamber above the cathode for receiving the molten light metal which rises from the cathode, 90 and a water-cooled partition separating such chamber from the space surrounding the anodes.

2. An electrolytic apparatus according to claim 1, having an anode chamber separated from such collecting chamber by such water-cooled partition, and adapted for maintaining a layer of material floating upon the electrolyte and surrounding and protecting the anodes.

3. An electrolytic apparatus for producing a metal lighter than the electrolyte, comprising a vessel for containing a molten fluorid bath, having an insulating layer of congealed salt on its bottom, a cathode projecting upwardly through such layer into the vessel, anodes depending into the vessel out of vertical alignment with the cathode, a collecting hood above the cathode for receiving the molten light metal which rises from the cathode, and means for cooling the upper portion of the bath located adjacent to the collecting hood, whereby to congeal the bath between the latter and the cooling means, and thereby seal the intervening 11 space.

4. An electrolytic apparatus according to claim 1, wherein the collecting hood is formed by a hollow shell filled with insulating material.

5. An electrolytic apparatus according to claim 1, wherein the cathode projects through the bottom of the vessel, is enlarged beneath the latter to receive the weight of the vessel, and rests upon a con- 13

ducting plate or bus-bar with which circuit connections are made, which plate in turn rests upon a supporting block.

6. An electrolytic apparatus for producing a metal lighter than the electrolyte, comprising a vessel for containing a molten bath, an anode and a cathode out of vertical alinement, the cathode being interposed between the anode and a wall of the vessel, a collecting chamber above the cathode for receiving the molten light metal which rises therefrom, the inner side of the collecting chamber comprising cooling means to maintain a salt incrusted curtain.
10. An electrolytic apparatus for producing a metal lighter than the electrolyte, comprising a vessel for containing a molten bath, cathodes extending along the sides of the vessel, anodes between the cathodes, collecting chambers above the cathodes for receiving the molten light metal which rises therefrom, the said chambers extending from the sides of the vessel inward to a point between an anode and a cathode.
15. An electrolytic apparatus for producing a metal lighter than the electrolyte, comprising a vessel for containing a molten bath, cathodes extending along the sides of the vessel, anodes between the cathodes, collecting chambers above the cathodes for receiving the molten light metal which rises therefrom, the said chambers extending from the sides of the vessel inward to a point between an anode and a cathode.
20. An electrolytic apparatus for producing a metal lighter than the electrolyte, comprising a vessel for containing a molten bath, cathodes extending along the sides of the vessel, anodes between the cathodes, collecting chambers above the cathodes for receiving the molten light metal which rises therefrom, the said chambers extending from the sides of the vessel inward to a point between an anode and a cathode.
25. An electrolytic apparatus for producing a metal lighter than the electrolyte, comprising a vessel for containing a molten bath, cathodes extending along the sides of the vessel, anodes between the cathodes, collecting chambers above the cathodes for receiving the molten light metal which rises therefrom, the said chambers extending from the sides of the vessel inward to a point between an anode and a cathode and comprising cooling means on their inner sides to maintain a salt incrusted curtain.
30. An electrolytic apparatus for producing a metal lighter than the electrolyte, comprising a vessel for containing a molten

bath, cathodes extending along the sides of the vessel, anodes between the cathodes, collecting chambers above the cathodes for receiving the molten light metal which rises therefrom, the said chambers extending from the sides of the vessel inward to a point between an anode and a cathode and comprising a metal plate located near the surface of the bath.

35. An electrolytic apparatus for producing a metal lighter than the electrolyte, comprising a vessel for containing a molten bath, cathodes extending along the sides of the vessel, anodes between the cathodes, collecting chambers above the cathodes for receiving the molten light metal which rises therefrom, the said chambers extending from the sides of the vessel inward to a point between an anode and a cathode and comprising a metal plate located near the surface of the bath, and means for counteracting radiation from the molten bath through the plate.

40. An electrolytic apparatus for producing a metal lighter than the electrolyte, comprising a vessel for containing a molten bath, an anode and a cathode out of vertical alinement, the cathode being interposed between the anode and a wall of the vessel, a collecting chamber above the cathode for receiving the molten light metal which rises therefrom, and comprising a metal plate located near the surface of the bath, and means to prevent freezing of the electrolyte to said plate.

45. In witness whereof, I have hereunto signed my name.

GEORGE O. SEWARD.
